Inventor;
A. Steward.

United States Patent Office.

A. STEWARD, OF PLANO, ILLINOIS.

Letters Patent No. 79,023, dated June 16, 1868.

IMPROVED THREAD-SHOW-CASE.

The Schedule referred to in these Letters Patent and making part of the same.

TO ALL WHOM IT MAY CONCERN:

Be it known that I, A. STEWARD, of Plano, in the county of Kendall, and State of Illinois, have invented a new and improved Thread-Show-Case; and I do hereby declare that the following is a full, clear, and exact description of the construction and operation of the same, reference being had to the annexed drawing, making a part of this specification, and to the letters of reference marked thereon.

The drawing shows the thread-case, filled with spools of thread, in working order.

Parts lettered as follows:

A, end of case; B, top of same; C, fascia; D, partitions; E, stops; F, spools of thread; G, shelves, forming inclined planes.

I construct my case as follows:

I make, of thin boards, or any other suitable material, a part of a box or case, that is to say, the top, ends, and back of one, one end of which is shown at A, and the top at B. The back and one end not shown in the drawing. Between these ends, I place a series of floors or shelves, G, dividing the space into a succession of lofts or stories. The front edge of the lower shelf is placed at the bottom of the case, while its back edge is elevated, forming an inclined plane, rising at the rate of, say, two inches per foot. The shelves above this one are placed in their due order above it, with the same inclination, and consequently parallel with it from front to back. The position of these shelves is indicated by the dotted lines on the end of the case. These several stories I also divide, by partitions, into chambers or cells, the ends of which partitions are shown at D D, &c.

As spool-thread is graded in fineness, and the spools are made in size to correspond, I graduate the cells accordingly by placing one end of the shelves nearer together than the other, and narrow the cells to accommodate the length of the spools, leaving only space enough between the partitions to allow the spools to roll freely, and space enough between the shelves to permit the spools to be raised in removing them from the case, as hereafter described. The vacant space in front, over the upper cells, I cover with a fascia, as shown at C in the drawing.

It will now be seen that spools placed within these cells, sloping forward as they do, will roll out unless prevented. To prevent this rolling out, I fasten a cleat upon the front edge of each shelf, wide enough above the shelf to stop the spools, which cleats are shown at E, and which I will call stops. As a substitute for this form of stop, a short perpendicular peg may be inserted into the shelf at the verge of each cell, or any other equivalent device may be adopted; but I prefer the cleats.

The front ends of the partitions, together with the corresponding portions of the ends of the case, are pared away, as seen in the drawing, in arc-form. This is done to allow the thumb and finger to the more readily take hold of the spool. Now, above these cells, I place the respective numbers of the spools which the cells are to contain, as seen in the drawing.

It may be constructed to contain any variety of colors, range of numbers, or kinds of thread. This show-case is designed more particularly for the use of merchants in retailing thread.

The cells are filled from the front, though, if desirable, the back may be left off and the filling done from the rear. Its operation is as follows:

Any number of thread sought for is found at a glance by the figures upon its cell. The spool is taken from the case by holding it between the thumb and finger and lifting it over the stop E, when those behind it immediately roll forward till the next spool strikes the stop; the next spool automatically taking the place of the one removed, thus keeping the whole assortment continually in view.

What I claim as my invention, and desire to secure by Letters Patent, is—

The show-case for containing spools of thread, consisting of the ends A, top B, partitions D, stops E, and inclined planes G, substantially as specified.

A. STEWARD.
